*Denison Williams.
Letters Patent*

The Schedule, referred to in these Letters Patent, and making part of the same, containing a description in the words of the said Denison Williams himself, his improvement in the manufacture of Moccasins, Breeches, Boots, Shoes, Mittens, Gloves &c. out of seal skins.

The object of this manufacture is to protect the body from the cold & moisture of the air, for which fur or hair is the best material, and the seal skin is in many respects preferable to any other. In order to prepare the skin for use, the flesh side is oil dressed, the mode of operation being somewhat similar to that used in dressing buck skin.

The composition used by this applicant consists of seal oil, pot ash, pyrogallic acid, & salt & sometimes sal ammoniac as the state of the skin may require, the proportions of which are to be varied according to the state of the skin to be

dressed, with a solution of which ingredients the skin is infused by the aid of heat & friction until it becomes sufficiently pliable; tough & insoluble in water.

The skin thus prepared, may be used for mittens, gloves, sleigh robes, moccasins, & the upper leather or material of socks, shoes, boots, &c. The fur or hair side being turned inward.

The soles of moccasins & socks to be made of any kind of leather lined with usual soakers, but not of the thickness of common sole leather, & turned up half an inch or more in order to protect the feet from the heat, & the soles of boots & shoes to be made in the usual manner.

The sole is lined with the same kind of fur or hair skin, which is made to adhere closely by paste of gum shellac, or other suitable substance, which is put on in sufficient quantity to exclude water.

Alum & some other chemical ingredients, may be used for dressing the skin in some instances, as well as the seal oil, alkali, pyrogallic acid, salt & sal ammoniac.

The applicant claims as his invention the manufacture of seal skins dressed in the manner above described with the fur or hair on, into socks, moccasins, shoes, sleigh robes & other winter garments.
